UNITED STATES PATENT OFFICE.

WILLIAM WALTER OWEN, OF OAK PARK, ILLINOIS, ASSIGNOR, BY MESNE ASSIGNMENTS, TO AUTOMATIC ELECTRIC INC., OF CHICAGO, ILLINOIS, A CORPORATION OF DELAWARE.

AUTOMATIC TELEPHONE SYSTEM.

Application filed March 10, 1919. Serial No. 281,779.

To all whom it may concern:

Be it known that I, WILLIAM WALTER OWEN, a citizen of the United States of America, and a resident of Oak Park, in the county of Cook and State of Illinois, have invented certain new and useful Improvements in Automatic Telephone Systems, of which the following is a specification.

My invention relates in general to an automatic telephone system and more specifically to improved switches for use in such a system to extend connections between subscribers' lines.

Among the objects of my invention are to provide improved impulse controlled motor driven switches which are noiseless in their action and which operate definitely and accurately without the enormous wear and tear occasioned by the operation of a switch which is driven by a ratchet and pawl arrangement. The switch I have provided while being of a motor driven type is also of a step by step type which arrangement is thought to be new in a two motion switch. I have also so arranged the apparatus of this switch so that only one motor magnet is needed as will be explained. The motor being controlled by impulses and adapted to step the wipers of the switch in one plane to select groups of lines or trunks by the first series of impulses and to then automatically step the switch in another plane to select an idle trunk in the case of the selectors and in the connector the second series of impulses controls the same motor magnet to step the wipers into connection with the desired line in the selected level.

These and other objects of my invention will be pointed out more in detail in the following explanation in which I will describe the operation of the switches disclosed in the accompanying drawings, when the subscriber A (Fig. 4) removes his receiver to establish a connection with the subscriber A', Fig. 5.

Figs. 1, 2 and 3 show the mechanism of the switch employed and the method of applying the motor magnet to either raise or rotate the wipers.

Fig. 4 shows a calling substation A having access through a line switch C to a selector switch D of my improved type.

Fig. 5 shows a connector switch H which is of my improved type and which is accessible, together with others, to the selector D (Fig. 1), and which may be operated to connect with one of a number of called lines such as the line A' having its associated line switch C'.

Referring to Figs. 1, 2 and 3, I will first describe the mechanism of the switch as shown in this figure. The selector and connector both having this same operating mechanism except that a somewhat different method of control is exercised in each case.

In Fig. 1 I have shown the motor magnet which drives the switch but I will explain its operation only in general as it forms the subject of a separate application, Serial No. 259,062, filed October 21, 1918, by John Erickson, and issued as Patent No. 1,493,254, May 6, 1924. The motor consists of a pair of operating magnets 4 and 5 mounted between a pair of brass brackets 7 and 8 and having pole pieces 9, 10, 11 and 12 extending inwardly to act upon the armature. The armature consists of a shaft 15 pivoted at points 13 and 14 in the brass plates 7 and 8 and having a brass piece 16 fastened thereto and carrying, firmly secured thereto, an iron element 18 which is so formed that one edge of its outer surface is heavier than the other. Now when the armature is standing in the position shown and the magnet 4 is energized, the pole pieces 9 and 10 cause the armature to rotate, with its thin edge advancing toward said pole pieces until it stands in such a position that the heaviest portion of the armature is close to the pole pieces 9 and 10. Then when the magnet 5 is energized the rotation of the armature will be continued in the same direction another half turn. Thus it will be seen that an impulse to magnet 4 and another to magnet 5 causes the shaft 15 to make a complete rotation.

On the outer end of the shaft 15 is a worm gear 19 which is mounted on the shaft 15 by a flexible spring connection 20, so that as the magnet 21 is energized, the gear 19 is moved into engagement with the gear wheel 31. Also mounted on the shaft 15, inside the flexible link 20 is a gear wheel 22 firmly secured to the shaft 15.

In Fig. 2 I have shown a front view of

the switch mechanism which consists of a vertically movable shaft 24 which moves in the bearings 25 and 26 in the frame of the switch. A combined gear rack and ratchet 27 is mounted on said shaft securely and moves therewith. A gear 28 is shown for raising the shaft 24 by means of the gear rack 27. The usual double dog such as is used in the Strowger type of switch is 10 adapted to hold the shaft 24 in its raised position by means of its upper tooth 29.

On the lower end of the shaft 24 is a sleeve 30 which moves vertically with the shaft and carries the wipers of the switch 15 mounted on its lower end. This sleeve is adapted to be rotated on the shaft 24 by means of a gear wheel 31 and a pin 32. This pin 32 moves through an opening in the gear wheel 31 as the shaft is raised, the 20 gear 31 being stationary while the shaft is raised. A spring is provided for returning the sleeve to its normal rotary position with regard to the shaft 24 when the double dog releases the gear 31. This gear 31 is 25 rotated by means of the worm gear 19 described in connection with Fig. 1 when the magnet 21 is energized.

Referring now to Fig. 3, I have shown a 30 side view of the switch frame and mechanism showing the motor magnet 5 and the method of causing this magnet to raise the shaft 24 by means of the gear wheel 28 and the gear rack 27. The gear wheel 28 is mounted on a shaft 34 which is mounted in 35 bearings at each end thereof, one end in the bracket 35 and the other end in the bracket 36 which also supports the magnet 37. This shaft 34 is movable lengthwise for a short distance and is normally held in its farthest 40 position to the right by the tension of a spring 38 which bears against the left end of the shaft 34. At this time, that is normally, the gear wheel 28 is out of engagement with the teeth of the gear rack 27. Now when 45 the magnet 37 is energized its armature presses against the right end of the shaft 34, moves said shaft to its farthest position to the left and brings the teeth of gear wheel 28 into mesh with the gear teeth of rack 27. A pinion wheel 39 is also firmly mounted 50 on the shaft 34 and meshes with the teeth of another gear wheel 40 which meshes on the opposite side with the teeth of the gear wheel 22. It will be seen that as the motor 55 magnet 37 is energized the rotary movement is communicated through gears 22, 40, 39 and 28 to the gear rack 27. These gears are so proportioned that a complete revolution of the gear wheel 22 causes the shaft to take one step upward or the distance between a 60 pair of rows of contacts in the bank of the switch. These gears may be arranged in any desired proportion, that is, one operation of the gear 22 may cause the gear 28 to en-

gage two teeth of the gear rack 27, but in any case the wipers take only one step. The usual double dog is used in this switch and is released from under its locking spring or release link by an arm on the armature of 70 magnet 37. That is when magnet 37 energizes to move the shaft 34, the double dog is released and engages the ratchet teeth on the vertical side of the shaft 24 with one of its dogs and engages the teeth of a ratchet 75 wheel 41 which is firmly secured to the gear wheel 31. When the usual release magnet energizes it forces the double dog out of engagement with the teeth of the ratchets and under the release link where it is held. 80

I will now describe the operation of the circuits applied to this switch and which are shown in the other Figures 4 and 5.

When the subscriber at substation A removes his receiver a circuit is closed for 85 the line relay 50 of the line switch C which operates to close a circuit for relay 51 and magnet 52 in series, and also closes a short circuit about relay 51 to the private wiper, so that if the trunk line upon which the 90 switch is resting is busy ground will be connected directly to the rotary magnet 52 to operate the same to step the wipers to the next contact and also to interrupt its own circuit. The magnet 52 continues its 95 operation until an idle trunk line is reached; at which time relay 51 is no longer shorted out and will energize in series with rotary magnet 52 to disconnect the line from the relays of the switch C and connect it to the seized trunk line. Magnet 52 does not energize over this series circuit due to the high resistance of relay 51.

As soon as relay 51 energizes a circuit 100 is closed for the line relay 53 of the selector D (Fig. 4), which relay energizes to close a circuit at springs 54 and 55 for relay 56. Relay 56 now energizes to ground the release trunk to the switch C at springs 105 58 and 59, closes a circuit for the magnet 37 from ground through springs 58 and 60, springs 61, springs 62 and 63, and magnet 37 to battery. Magnet 37 energizes at once 110 to bring the gear 28 into mesh with the teeth of the gear rack 27, Fig. 2. Relay 56 also prepares one point in a circuit of magnet 5 of the motor magnet at springs 57, and closes one point in the circuit of magnet 4 of the motor magnet and of relay 64 at 115 springs 65 and 66.

When the calling subscriber now operates 120 his calling device for the first digit of the called number, relay 53 falls back a number of times in response thereto and upon falling back closes a circuit for magnet 4 at 125 springs 54 and 67 and also completes the circuit of relay 64 at said springs. The energization of magnet 4 causes the shaft of the motor magnet to move 1/2 step and as relay 53 energizes again the circuit of mag- 130

net 5 is closed through springs 54 and 55, springs 57, and springs 68, which completes the full first step of the switch shaft and steps the wipers opposite the first level of 5 contacts in the bank. Each time the relay 53 falls back and pulls up again therefore magnet 4 receives an impulse of current and then magnet 5 receives an impulse. Relay 64 which is slow acting, remains energized 10 during this first series of impulses and maintains the circuit of relay 69 open at springs 70 and 71. Now, however, as soon as relay 53 comes to rest energized after this first series of impulses, relay 64 will fall back 15 and close the circuit of relay 69 at springs 70 and 71 and through the off normal springs 72 which were closed after the first vertical step of the switch shaft. Relay 69, upon energizing, opens the circuit of relay 64 20 at springs 73, opens the circuit of magnet 37 at springs 62 and 63, closes the circuit of magnet 21 at springs 62 and 74, prepares a new circuit at springs 75 for the motor magnet 5, and closes a circuit momen- 25 tarily through springs 76, 77 and 78 for the relay 79. It will be seen that the shaft has now been raised to a desired level where it is being held in position by the double dog and that the magnet 21 has now brought 30 the worm gear 19 into engagement with the gear wheel 31 in readiness to rotate the hub to carry wipers around over the contacts in this level. When relay 79 energizes due to the momentary impulse given it by relay 69, 35 said relay 79 attracts its armature to close a circuit for motor magnet 4 at springs 80 and 81 and then deenergizes to close a circuit for magnet 5 through springs 80 and 82 thus causing the worm gear 19 to move 40 the hub carrying the wipers so as to bring said wipers into engagement with the first set of contacts of the bank level selected. As soon as relay 79 falls back and closes its springs 83 a circuit is prepared for itself 45 extending to the private wiper 84. Now, if the trunk line associated with this first set of contacts is busy and a ground is present on the test contact thereof, then relay 79 will again be energized to transmit another 50 impulse to each of the magnets 4 and 5 and to open its own circuit at springs 83. Relay 79 continues to operate in this manner to step the wipers over busy contacts until an idle trunk line is found on the test contact 55 of which is no guarding ground. At this time a circuit becomes effective as follows: Ground through springs 58 and 59, relay 85, springs 86, springs 83, and magnet 79 to battery. Relay 85 is of higher resistance 60 than relay 79 and relay 79 therefore does not energize in this circuit. Relay 85 energizes to hold the release circuit open at springs 87, opens the circuit of magnet 21 at springs 61, disconnects the private wiper 65 84 from relay 79 and connects it direct to ground through springs 58 and 59 to hold relay 85 energized. Relay 85 also opens the circuit of the line relay 53 and connects the line through the wipers 88 and 89 to the seized trunk line. Relay 53 being slow acting holds the ground on the private wiper to keep relay 85 energized until ground is supplied thereto from the seized switch. As soon as relay 85 closes this last circuit, 70 the line relay 90 of the connector H (Fig. 5) 75 is energized over the line circuit and closes a circuit for relay 91 at springs 92 and 93. Relay 91 operates to ground the release trunk to the switch D through springs 94 and 95, closes a circuit for the magnet 37' 80 at springs 94 and 96, through springs 97 and 98 and springs 100. Magnet 37' operates as before pointed out in connection with magnet 37 in the other figures to prepare the gears so that when the motor magnet is operated the shaft and wipers will be raised. Relay 91 also completes a circuit at springs 101 for motor magnet 5' (this does not move the switch due to the position of the armature at this time), and at springs 102 and 103 85 90 a circuit is prepared for motor magnet 4' and also for relay 104. Now when relay 90 responds to the impulses of the next digit it vibrates a number of times and on each deenergization closes a circuit from ground through springs 92 and 105, springs 102 and 103 through magnet 4' to battery, and also through springs 106 and relay 104 95 to battery. Then as relay 90 attracts its armature it again closes a circuit through springs 92 and 93, springs 101, and magnet 5' to battery. Thus each falling back and pulling up of relay 90 causes the gear shaft of the motor magnet to make one complete revolution and therefore steps the shaft carrying the wipers one step to the first level of contacts. Relays 91 and 104 remain energized during this digit and relay 104 while energized maintains the circuit of relay 107 100 open at springs 108 and 109. Now as soon 105 as the impulses for this digit cease and relay 90 comes to rest energized, relay 104 will fall back and close the circuit of relay 107 which has been completed by the off normal springs 110. Relay 107 energizes to open the circuit of relay 104 at springs 106, prepares a circuit for the relay 111 at springs 112, opens the circuit of magnet 37' 110 at springs 97 and 98, closes the circuit of magnet 21' at springs 97 and 99. Magnet 21' 115 now energizes to bring the worm gear 19 of the motor magnet into operative engagement with the rotary gear wheel 31 in readiness to rotate the wipers over contacts in the selected level. As the next series of impulses are sent to relay 90 said relay again 120 operates the magnets 4' and 5' in this case rotate the wipers over contacts in the elected level to a certain set of contacts to which are connected the conductors leading to the 125 130

line of the desired subscriber. The relay 111 energizes and remains energized during this series of impulses to connect the private wiper 113 to the busy relay 114. Now, if 5 the called line is busy and a ground is present on the test contact thereof, then as soon as the wipers stop on the contacts of the line a circuit is completed for the relay 114 from the ground on the wiper 113. Relay 10 114 will energize to connect the busy signal to the calling line and lock energized as soon as relay 111 falls back whereupon the connection may be released by the restoration 15 of the receiver at the calling station in the usual manner. If, however, the called line is idle, then relay 114 will not energize and relay 111 will fall back an instant after impulses cease to close the circuit of wiper cut on relay 115. Relay 115 energizes over 20 a circuit from ground on the release trunk through its upper winding, springs 116 and 117, springs 118 and 119, wiper 113, and through the bridge cut off relay of the called party's line switch C' to battery. Relay 115 25 locks itself energized through springs 120, closes the called line through the ringing circuit at springs 121 and 122, and connects ground direct to the private wiper through springs 119 and 123. Interrupted generator 30 current will now flow through the ringer at the called substation in series with the relay 124 and as soon as the called subscriber answers relay 124 energizes to disconnect the called line from the generator circuit, and 35 locks itself energized. The back bridge relay 125 is energized in series with the called line and in operating opens the circuit of relay 107 at springs 126 and opens the circuit of magnet 37' at springs 100. Conversation 40 may now proceed over the heavy conductors shown in the drawing and when completed the connection may be released as follows: When the circuit is opened at the calling station by the hanging up of the 45 receiver the line relay 90 of the connector falls back and opens the circuit of relay 91 which in turn deenergizes and completes the circuit of the release magnet 130. Magnet 130 operates to withdraw the double 50 dog from the teeth of the ratchets by which it is holding the wipers in their advanced position, thus allowing the hub or sleeve 30 to rotate back off the contacts in the level and then the switch shaft 24 will drop to 55 its normal vertical position. Magnet 130 also closes a circuit for the motor magnet 5' to insure that the armature of the motor magnet always stands normally so that an energization of magnet 4' will cause one half 60 turn of the armature.

Also when relay 91 deenergizes the holding ground is removed from the release trunk to the switches D and C. Relay 85 of the switch D therefore falls back to close 65 the circuit of release magnet 131 which op-

erates in the same manner as magnet 130 of connector H. Relay 51 of the line switch C also deenergizes at this time to prepare the line switch for the next call.

It will be seen therefore, that I have 70 provided a highly efficient type of two motion switches which operate by impulses in the well known manner used in the Strowger type of automatic switch and which are 75 silent in operation and entirely without the disadvantages encountered in the ratchet driven type of automatic switch.

Having fully described and ascertained the features and aspects of my invention, 80 what I consider to be new and desire to have protected by Letters Patent will be pointed out in the appended claims.

What I claim as my invention is:

1. In a telephone system, an automatic switch having wipers, trunk lines accessible thereto divided into groups, a motor for moving said wipers, means for operating said motor by impulses corresponding to the digits of a called number, a revolving armature for said motor and means for causing said armature to first move said wipers in one plane and then in another plane in response to said impulses to seize one of said trunk lines. 90

2. In a telephone system, an automatic switch, trunk lines accessible thereto, a motor having an armature for operating said switch, said armature being movable in one direction only, means for operating said motor by a plurality of series of impulses, and means for causing said motor to operate said switch in one plane to pick out a group of trunk lines in response to the first series of impulses and to operate said switch in another plane to pick out a line in the selected group in response to the next series of impulses. 100

3. In a telephone system, an automatic switch, a motor for operating said switch, a revolving armature for said motor, a shaft for said switch carrying wipers, means for first gearing said armature to the shaft in such a manner that the shaft will be raised by the operation of the motor, and means for then gearing the said armature to the shaft in such a manner that the shaft will be rotated by the operation of the motor, and means for operating the same by transmitting series of impulses to said motor. 110

4. In a telephone system, an automatic switch, a magnetic motor for the switch, trunk lines accessible to the switch divided into groups, a calling device for transmitting impulses to said motor, said motor having a single revolving armature responsive to a series of said impulses to elect a group of said trunk lines and automatically operated to select an idle trunk line in the elected group. 120

5. In a telephone system, an automatic 130

switch, a shaft for said switch, a gear for raising said shaft and another gear for rotating the same, a calling device for transmitting impulses to operate said switch, a 5 motor magnet controlled by said impulses, and means for first associating said motor magnet with the gear to raise the shaft, and for then associating the magnet with the other gear to rotate the shaft:

10 6. In a telephone system, lines, a calling device for each line, automatic switches accessible to the lines for extending connections therefrom, a motor magnet for each switch, a wiper carrying element for each 15 switch, a series of gears operated by each motor magnet, means for operating the motor magnet of a seized switch in response to impulses from a calling device, and means for associating certain of said gears of the seized switch with the associated element to move the element in one direction while the motor magnet is operating, and for associating another of said gears with the element to move it in another direction while 20 the motor magnet is operating.

7. In a telephone system, lines, calling devices therefor, an automatic switch accessible to a calling one of said lines for extending connections therefrom, a motor 25 magnet for said switch controlled by the calling device on the calling line, a worm gear and a gear wheel driven by said magnet whenever it operates, and a pair of clutch magnets, one of said clutch magnets being 30 operable to connect said gear wheel with the wiper carrying element of the switch to move it in one direction and the other clutch magnet being operable to connect the worm gear to said element to move it in another 35 direction.

40 8. In a telephone system, a line, a switch for said line, a wiper carrying element for the switch, a motor for the switch, a series of gears controlled by the motor, a calling 45 device for the line for sending a plurality of series of impulses to the switch, said motor operating in response to each series to move said gears, a clutch magnet which operates automatically to interconnect one of said 50 gears with the element only during the first series of impulses to move the same, and another clutch magnet which is operated automatically to interconnect another of said 55 gears to the element during the next series of impulses to move it in another manner.

9. In a telephone system, a line, a switch for said line, a wiper carrying element for the switch, a motor for the switch, a series of gears controlled by the motor, a calling 60 device for the line for sending a plurality of series of impulses to the switch, said motor operating in response to each series to move said gears, a clutch magnet which operates automatically only during the first series of

impulses to interconnect one of said gears 65 with the element to move the same, and another clutch magnet which is operated automatically during the next series of impulses to interconnect another of said gears to the element to move it in another manner, and 70 means for holding the element in its advanced position independent of the motor magnet.

10. In a telephone system, an automatic switch having a wiper carrying element 75 which is movable in two planes to extend connections, a motor for said switch having a shaft which always moves in the same direction, means for associating said shaft with said element to move the element in 80 both planes, subscriber controlled means for operating the motor when the said element is moved in one plane, and means for operating said motor independent of subscriber control when the said element is moved in 85 the other plane.

11. In a telephone system, an automatic switch, a motor for said switch having a shaft which always moves in the same direction, means for sending impulses to said 90 switch to operate the motor, an element carrying the wipers of the switch and movable in two planes, and means for causing said motor to operate said element in both planes.

12. In a telephone system, an automatic switch, a motor for said switch having a shaft which always moves in the same direction, means for sending impulses to said switch to operate the motor, an element 100 carrying the wipers of the switch and movable in two planes in a step by step manner, and means for causing said motor to operate said element in both planes.

13. In a telephone system, an automatic switch, a wiper carrying element in said switch having primary and secondary selecting movements in different planes, a motor individual to said switch for driving said element in both movements, said motor having a shaft which always moves in the same direction, and a subscriber controlled line relay in said switch for controlling the operation of said motor.

14. In a switching device for automatic 115 telephone systems, a main shaft movable longitudinally only, an auxiliary shaft movable longitudinally with said main shaft, said auxiliary shaft having also a rotary movement, and a subscriber controlled electromagnetic motor for operating both of said shafts as set forth.

15. In a switching device for automatic 120 telephone systems, a main shaft movable longitudinally only, a hollow auxiliary shaft 125 concentric with said main shaft and movable longitudinally therewith, said auxiliary shaft also having a rotary movement, and a subscriber controlled electromagnetic

motor for operating both of said shafts as set forth.

16. In a switching device for automatic telephone systems, a main shaft movable longitudinally only, an auxiliary shaft supported on and movable longitudinally with said main shaft, said auxiliary shaft having also a rotary movement, circuit closing

wipers supported on said auxiliary shaft, a subscriber controlled motor mechanism, and means for controlling said mechanism for operating either of said shafts as set forth.

Signed by me at Chicago, Cook County, Illinois, this 4th day of March, 1919.

WILLIAM WALTER OWEN.
